UNITED STATES PATENT OFFICE.

CLIFFORD BARGAMIN, OF NEWPORT NEWS, VIRGINIA.

TIME-CONTROLLED MECHANISM.

1,229,863.

Specification of Letters Patent. Patented June 12, 1917.

Application filed September 14, 1916. Serial No. 120,131.

To all whom it may concern:

Be it known that CLIFFORD BARGAMIN, a citizen of the United States, residing at Newport News, in the county of Warwick 5 and State of Va., have invented new and useful Improvements in Time-Controlled Mechanism, of which the following is a specification.

This invention relates to time controlled 10 trip mechanism, the object in view being to provide simple, reliable and efficient means for tripping or throwing into operation at a predetermined time, a controlling or actuating member of any suitable device or 15 mechanism, the trip mechanism being controlled by a spring motor such as clock mechanism which may be set to run for any desired length of time.

A further object of this invention is to 20 provide in connection with the tripping mechanism above referred to, means operating to automatically stop the spring motor or clock mechanism at or about the time the tripping mechanism is actuated.

25 With the above and other objects in view the invention consists in the novel construction, combination and arrangement of parts, herein fully described, illustrated and claimed.

30 In the accompanying drawing:

Figure 1 is a front elevation partly in section of the improved time controlled trip mechanism.

Fig. 2 is a sectional view thereof looking 35 in the same direction.

Fig. 3 is a transverse section on the line 3—3 of Fig. 2.

Referring to the drawings 1 designates a portion of the body of the article in conjunction with which the trip mechanism is employed, and 2 designates the controlling or actuating element to be tripped by the time controlled mechanism, the member 2 being shown in the form of a rod slidable 40 through one or more guides 3 and actuated by a spring 4, 5 designating a shoulder on the member 2 which is capable of being adjusted by means of a set screw 6.

50 A designates generally a spring motor embodying a mounting frame 7 which together with the spring motor mechanism is mounted within a casing 8 secured by means 9 to the body 1. 10 designates a latch shown in the form of the single leaf spring which is connected by fastening means 11 to one 55 wall of the casing. The latch 10 is provided

with a shoulder or latch lip 12 which is movable into and out of the path of the shoulder 5 on the member 2. Connected to the latch 10 is one extremity of a flexible 60 connection 13 such as a cord or cable, the other end of said connection 13 being attached to and wrapped around the winding arbor 14 of the spring motor or clock mechanism A.

65 On the front of the casing A is a stationary dial 15 and sweeping around said dial is a pointer or hand 16 which is fast on the arbor 14 outside of the casing 8. A stop arm 17 is also fast on the arbor 14 within 70 the casing 8 and said arm 17 is provided at its free end with a laterally extending finger 18 which is adapted to come into contact with the escapement lever 19 of the spring motor or clock mechanism when the 75 pointer or hand 16 returns to zero on the dial.

In order to set the mechanism, the hand or pointer 17 is turned to the left in Fig. 1 thereby winding the spring motor and setting the same to run for a predetermined number of minutes, the hand being shown in Fig. 1 as set for twenty minutes. The member 2 is shifted to the position shown in Fig. 1 so that the shoulder 5 thereof is upheld by the shoulder 12 of the spring latch 10. As the arbor 14 revolves under the action of the spring motor, the flexible connection 13 is wound around said arbor and when the hand 16 returns to zero, the shoulder 12 of the spring latch is drawn out from under the shoulder 5 of the member 2 thereby releasing the latter which is then acted upon by the spring 4. As the hand 16 reaches zero on the dial, the finger 18 of 85 the arm 17 comes in contact with the escapement lever 19 and prevents the further vibration or swinging movement thereof thus stopping the motor or clock mechanism.

100 The time controlled trip mechanism hereinabove described and illustrated in the drawings is especially designed for use in connection with automatic fireless cookers but it will of course be understood that said trip mechanism may be used in many other 105 connections which will readily suggest themselves to the manufacturer.

I claim:

110 1. The combination with a controlling member having a shoulder, of time controlled trip mechanism embodying a self-setting latch having a shoulder movable into

and out of engagement with the shoulder of said controlling member for holding and releasing the latter, a spring motor embodying a spring, a spring winding arbor, a flexible connection wound upon said arbor and attached to said latch, a dial, and a pointer fast on said arbor and also serving as a means for turning said arbor to wind the spring, simultaneously slack said flexible connection and permit the latch to reset itself.

2. The combination with a controlling member having a shoulder, of time controlled trip mechanism embodying a self-setting latch having a shoulder movable into and out of engagement with the shoulder of said controlling member for holding and releasing the latter, a spring motor embody-

ing a spring winding arbor and an escapement lever, a flexible connection wound upon 20 said arbor and attached to said latch, a dial, a pointer fast on said arbor and also serving as a means for turning said arbor to wind the spring motor, simultaneously slackening 25 said flexible connection and permitting the latch to reset itself, and a stop arm fast on said arbor and movable into and out of engagement with said escapement lever, for the purpose of stopping the motor when the pointer returns to zero.

In testimony whereof I affix my signature in presence of two witnesses.

CLIFFORD BARGAMIN.
